UNITED STATES PATENT OFFICE.

WILLIAM A. MOONEY, OF RICHMOND, VIRGINIA, ASSIGNOR OF ONE-THIRD TO
WILLIAM P. MAYO, OF RICHMOND, VIRGINIA.

PACKAGING-MACHINE.

1,401,273.

Specification of Letters Patent. Patented Dec. 27, 1921.

Application filed October 20, 1920. Serial No. 418,262.

To all whom it may concern:

Be it known that I, WILLIAM A. MOONEY, a citizen of the United States, and a resident of Richmond, in the county of Henrico and 5 State of Virginia, have invented certain new and useful Improvements in Packaging-Machines; and I do hereby declare the following to be a full, clear, and exact description of the invention, such as will enable 10 others skilled in the art to which it appertains to make and use the same.

This invention relates to improvements in machines for packaging cigarettes and more particularly to means for controlling the 15 feed of the cigarettes,—one object of the invention being to provide simple and efficient means for stopping the feed of cigarettes when the wrapping foil for the packages breaks or becomes distorted or when a 20 cigarette breaks; my improvements being such as to enable the operator to use both hands in readjusting the foil.

A further object is to so construct the feed belt operating and controlling devices that 25 said belt may be readily adjusted to a small or to any necessary degree to take up slack when the cigarettes fail to lie properly on said belt.

With these and other objects in view the 30 invention consists in certain novel features of construction and combinations of parts as hereinafter set forth and pointed out in the claims.

In the accompanying drawings, Figure 1 35 is a side elevation of a portion of a cigarette packaging machine. Fig. 2 is a view at right angles to Fig. 1, and Figs. 3, 4 and 5 are detail views.

1 represents a suitable frame upon which 40 a hopper 2 is mounted and the latter contains a feed wheel 3,—all of which may be of any preferred construction. Wheels 4, 5, are mounted at respective ends of the horizontal portion of frame 1 and a feed belt 6 45 passes over these wheels so as to be disposed in position to receive cigarettes from the hopper 2. A shaft 7 on which the feed belt wheel 5 is located, has secured thereto a toothed clutch member 8 to coöperate with 50 a similar clutch member 9 mounted loosely on the shaft. These clutch members are provided with a considerable number of teeth (each of said members having, preferably, about forty teeth), for a purpose here- inafter explained. The clutch member 9 is 55 rigid with one end of a sleeve 10 mounted freely on the projecting end portion of the shaft 7 and at one end carries a sprocket wheel 11. The shaft 7 projects beyond the outer end of the sleeve 10 and is provided 60 with a head 12 between which latter and the end of the sleeve, a spring 13 is located to normally press said sleeve in a direction to cause engagement of the clutch member 9 with the clutch member 8. The sleeve 10 is 65 provided with a groove 14 which receives the forked upper end of a shift lever 15, the lower end of the latter being pivotally connected with a bracket 16 projecting from the lower portion of the framework. 70

A stop device 18 is pivotally supported by the depending portion of the framework and comprises two arms 19, 19, connected together at one end and at their free flaring ends provided with pins 20 to enter the 80 lower portion of the chute 17 through which the cigarettes, discharged from the feed belt, are conveyed to the packaging receptacle (not shown). 75

With these and other objects in view the 85 invention consists in certain novel features of construction and combinations of parts as hereinafter set forth and pointed out in the claims.

In the accompanying drawings, Figure 1 90 is a side elevation of a portion of a cigarette packaging machine. Fig. 2 is a view at right angles to Fig. 1, and Figs. 3, 4 and 5 are detail views.

1 represents a suitable frame upon which 95 a hopper 2 is mounted and the latter contains a feed wheel 3,—all of which may be of any preferred construction. Wheels 4, 5, are mounted at respective ends of the horizontal portion of frame 1 and a feed belt 6 passes over these wheels so as to be disposed in position to receive cigarettes from the hopper 2. A shaft 7 on which the feed belt wheel 5 is located, has secured thereto a toothed clutch member 8 to coöperate with 100 a similar clutch member 9 mounted loosely on the shaft. These clutch members are provided with a considerable number of teeth (each of said members having, preferably, about forty teeth), for a purpose here-

It sometimes happens that the cigarettes will not be properly spaced on the feed belt and may get out of proper relation to each other and in order to remedy this, it is necessary to move the feed belt by hand. For this purpose the shaft 7 is provided with a

hand wheel 28 and by providing clutch members, such as 8-9, with a large number of small teeth, the feed belt may be moved slightly (corresponding to the thickness of 5 a single cigarette) or it may be moved any necessary greater distance.

The feed belt is driven by a sprocket chain from any convenient source of power, passing over the sprocket wheel 11.

- 10 When the wrapping foil becomes broken, distorted or misplaced, the operator will move the shaft 25 by means of the hand lever 26 and this will cause coöperation of the cam block 24 with the upwardly projecting arm 23 of the stop device 18 to so operate said stop device as to cause the pins 20 to enter the chute 17 and thus stop the further passage of cigarettes from said chute to the packaging devices. The same operation of 15 the shaft 25 will cause the cam 27 to turn and, by engagement of said cam with the shaft lever 15, the latter will be caused to move outwardly and shift the sleeve 10 on the shaft 7, thus separating the clutch member 9 from the clutch member 8 and stopping the operation of the feed belt.
- 20
- 25

Various slight changes might be made in the details of construction of my invention without departing from the spirit thereof or 30 limiting its scope and hence I do not wish to restrict myself to the precise details herein set forth.

Having fully described my invention what I claim as new and desire to secure 35 by Letters-Patent, is:

1. In a packaging machine, the combination with a feed belt and a chute, of a stop-device coöperable with the chute, clutch devices for the feed belt, and manually oper- 40 able means coöperable with said stop device and said clutch devices for operating both simultaneously.

2. In a packaging machine, the combination with a feed belt, clutch devices for con- 45 trolling the operation of the same, and a chute, of a stop device coöperable with the chute and having an arm, a manually oper- able shaft, a device carried by said shaft, and coöperable with said arm of the stop 50 device for operating the latter, and means

for controlling the operation of said clutch devices.

3. In a packaging machine, the combination with a feed belt, clutch devices for the same, a shift lever for said clutch devices, 55 and a chute to receive articles from said feed belt, of a stop device coöperable with said chute, a manually operable shaft pro- vided with a part to operate said stop de- vice, and a cam carried by said shaft for 60 operating the shift lever to stop the feed belt when said stop device is operated.

4. In a packaging machine, the combination with a feed belt, a chute to receive articles therefrom, and a shaft carrying one 65 of the wheels for the feed belt, of a sleeve mounted loose on said shaft, a clutch member carried by said sleeve and having a multiplicity of teeth, a clutch member secured to said shaft and having a multiplicity of 70 teeth to mesh with the teeth of the first mentioned clutch member, a manually operable member secured to said shaft, manually operable means for shifting said sleeve and clutch member thereon, and means on said 75 sleeve to receive a driving member.

5. In a packaging machine, the combination with a frame having a horizontal and depending portion, a feed belt mounted in the horizontal portion of said frame, and a depending chute in the depending portion of said frame, of a shaft carrying one 80 of the wheels for the feed belt, driving means, clutch devices between said driving means and said shaft, a stop device pivot- ally mounted in the depending portion of the frame and having a plurality of arms provided with stop pins to enter said chute, a manually operable shaft, a cam on said shaft for operating said stop device, a shift lever for the clutch devices, and a cam carried by said manually operable shaft for 85 operating said shift levers.

In testimony whereof, I have signed this specification in the presence of two sub- 90 scribing witnesses.

WILLIAM A. MOONEY.
